FRANÇOIS GINET, OF CHAMBERY, FRANCE.

CAN-CLOSURE.

SPECIFICATION forming part of Letters Patent No. 769,899, dated September 13, 1904.

Application filed February 14, 1902. Serial No. 94,041. (No model.)

To all whom it may concern:

Be it known that I, FRANÇOIS GINET, a citizen of the Republic of France, and a resident of Chambéry, France, have invented certain new 5 and useful Improvements in Can-Closures, of which the following is a specification.

My invention relates to improvements in cans having soldered tops; and the object of the invention is to provide an improved form 10 of can-top of the rip-opening type—that is, of the type in which the can can be opened by winding up a strip of metal upon a suitable key.

The invention resides in the particular construction hereinafter described, and particularly set forth in the claim.

I have illustrated the invention in the accompanying drawings, in which—

Figure 1 represents a central vertical section through the upper portion of the can. Fig. 2 is a perspective view of the upper part of the can, showing the manner of opening.

Referring to Figs. 1 and 2, the upper end of the can, as indicated at *b*, and a cover which 25 is applied thereto is shown as consisting of two parts 1 and 2, connected by a band 3, which overlaps the adjoining edges of the parts 1 and 2 and is soldered thereto. The part 1 is in the shape of a ring provided with 30 an open center and having its outer edge clamped or folded around the upper edge of the can-body. The inner edge of the ring is depressed below the upper end of the can-body, but lies in a horizontal plane. The central 35 portion or disk 2 has its peripheral edge portion 2^a struck downwardly, as shown. Thus when the depressed portion 1^a of the ring 1 and the portion 2^a of the disk 2 are held in alinement a shallow depression is formed. 40 Within this shallow depression is located the joining-strip 3, which is simply a circular strip of metal having one end slightly overlapping the other. This, it will be seen, overlaps both portions 1^a and 2^a and is soldered to 45 both, as indicated clearly in Fig. 1, thus securing the parts effectively together. When, however, it is desired to open the can, a suitable tool, such as that indicated at *c* in Fig. 2, is connected to the free end *p* of the

strip 3, and by winding up the key the strip 50 may be pulled away from the surfaces to which it is soldered, and thus the disk 2 left entirely unconnected with the ring 1.

I am aware that it is not new to embody a wire or ripping-strip in or beneath the metal 55 of the can so that it has a ripping effect to cut or sever the joint or corresponding portion of the can in opening the same. I am also aware that it is not new to provide parallel weakened lines and to rip out the portion of 60 metal lying between said parallel lines; but my invention is clearly distinguished from this in that I provide a can-top of two parts having their edges adjacent to each other, but not in contact, the connecting and closing ef- 65 fect being secured by a strip of metal which overlaps the said adjacent parts and has its face soldered to the faces of the said parts, so that when the strip is pulled away the parts are left entirely unconnected without any part 70 of either being torn or ruptured in any way.

By constructing my can top or cover as above described I avoid the necessity of having the ripping-strip sever the tin of the cover, while at the same time after the soldered strip is removed the inner part is left 75 entirely disconnected with the outer. There is therefore no danger of breaking of the ripping-strip before the opening of the can is effected.

A further advantage of my construction lies in the fact that as the inner part is smaller than the outer part the two parts may be struck at one and the same time out of a single sheet of metal without waste, while by locating the joining-strip in a depression, as described, the strip does not project above the top of the can, but is protected and space saved when the cans are piled one above the other.

A still further advantage in my construction is that I have found it more convenient to manufacture and easier to assemble, and hence more economical, than any rip-openers of which I am aware.

Having thus described my invention, what I claim is—

The combination with a metallic can-body

of a two-part cover comprising an outer part having its outer edge engaging the edge of the can-body and having a depressed inner portion, an inner disk having a raised central part with a depressed outer edge, the depressed portions of the inner and outer parts forming an annular channel and a flat annular band of sheet metal soldered to the bottom of said channel and having a projecting end for

engagement with a suitable key, substantially as described.

In witness whereof I have hereunto set my hand in presence of two witnesses.

FRANÇOIS GINET.
